WO 90/09651 8/1990 WIPO*Primary Examiner*—B. J. Bullock
Attorney, Agent, or Firm—Scully, Scott, Murphy & Presser**[57] CLAIM**

The ornamental design for a garment hanger, as shown and described.

DESCRIPTION

FIG. 1 is a front elevational view of our new design;
 FIG. 2 is a rear elevational view of FIG. 1;
 FIG. 3 is a right end elevational view of FIG. 1;
 FIG. 4 is a left end elevational view of FIG. 1;
 FIG. 5 is a top plan view of FIG. 1; and,
 FIG. 6 is a bottom plan view of FIG. 1.
 The clip ends of the garment hanger are for illustrative purposes and form no part of the claimed design.
